UNIVERSAL SCREEN FOR PREPARING
HALF-TONES

Charles W. Bennett, Douglaston, N. Y., assignor,
by direct and mesne assignments, to Photo-
Cast, Inc., Rochester, N. Y., a corporation of
New York

Application March 3, 1933, Serial No. 659,487

1 Claim. (Cl. 95—81)

This invention relates to screens for making half-tones photographically and has for its object to provide a screen for universal application as well as a method of producing the same which 5 will be cheaper in manufacturing costs and more efficient to use than those heretofore proposed.

With these and other objects in view the invention resides in the novel steps and combinations of steps constituting the method of production, as well as in the novel article produced thereby, all as will be disclosed more fully herein-after and particularly pointed out in the claim.

Referring to the accompanying drawing forming a part of this specification in which like numerals designate like parts in all the views,—

Fig. 1 is a diagram illustrating the method of determining the screen separation distance;

Fig. 2 is a diagram illustrating the method of determining the coverage with a light intercepting screen of given opening when using the largest diaphragm opening; and

Fig. 3 is a representation, greatly magnified, of a portion of the contact screen produced by my method.

In order that the precise invention may be more clearly understood it is pointed out that contact half-tone screens heretofore produced are of a character which do not properly render the values of the picture to be reproduced. It is 30 obvious that if extreme contrast must be registered, the screen must be capable of delineating a range of contrast from point black to point white. This necessitates a cut-out to the minimum light on one end of the scale and a complete 35 cut-out of the maximum light on the other end of the scale. It may be seen therefore that what is required is a density wedge with maximum density at a point and sufficient to intercept at that point all of the maximum light. The 40 density should decrease from the maximum point to a minimum point at which minimum point all of the minimum light reflected from a picture to be reproduced, should be cut out. It may readily be seen that this would enable the production of a tone scale ranging from black to white. The variation in between the two extreme points may be gradual or in steps.

In the production of such a density wedge for the purpose above meant, it is obvious that the 50 extreme dense portions up to the maximum point must be light enough so that a print through may be obtained by the maximum light. At the same time, on the other extreme, the density must be light enough so that feeble lights above 55 the minimum are registered. This means that

the total area of a usable screen must be covered but the extremes are limited as mentioned above. Contact screens have been made heretofore by interposing a cross line screen between a diaphragm and the screen supporting medium. This cross line screen has been placed in what is known as half-tone relation with respect to the screen supporting medium. It is pointed out that with the screen in half-tone relation to the screen supporting medium, a complete coverage 10 of the areas extending between maximum and minimum density required, as pointed out above, could not be had without obtaining a density too great at the dense portion.

I have discovered that the densest portion of 15 the screen can be prepared with a gradual shading to the minimum portion in the following manner. A camera set up is obtained with a lens diaphragm system and a contact screen supporting medium, with a cross line or other 20 light intercepting screen interposed between the two, and although in the following disclosure reference is made by way of example to a cross line screen, it is to be understood that my invention contemplates screens having lines otherwise formed as well as lines, dots, or figures 25 creating geometric or other designs. A light source is used which may consist of the light reflected upon a surface as for instance a sheet of paper with a set up as in ordinary process 30 copy work. It has been found that the use of minute openings for minimum diaphragm exposures will produce the desired result. These 35 openings are essentially smaller than those used in ordinary copying work for a given lens and light system.

A minimum diaphragm opening is selected, and the cross line screen separation calculated so that, with the minimum diaphragm above mentioned, the primary beams of light, passing through the cross line screen openings, will focus at the emulsified surface of the contact screen supporting medium. For example with a camera extension of 29 $\frac{1}{4}$ inches, with an 18 inch focus lens, a diaphragm opening of 0.075 inch, and a cross line screen opening of

1
120
inch the following ratio

$$11\frac{1}{4}:X=0.075:\frac{1}{120}$$

where X equals the screen separation and 11 $\frac{1}{4}$ equals the difference between the camera exten- 55

sion and the focal length of the lens, will result in a value of $1\frac{1}{4}$ inches which is the amount of screen separation which I have found most desirable for the best results.

5 This has been diagrammatically illustrated in Fig. 1 wherein 2 and 3 indicate outer beams of the light entering the camera through the minimum diaphragm opening 4 (enlarged for the purpose of illustration) and passing through an 10 opening (also enlarged) of the light intercepting screen 5, focusing upon the light sensitive surface of the contact screen 6. The dot and dash lines indicate a foreshortening of the camera set-up in order to accommodate the diagram to 15 the sheet of drawings, and the various dimensions hereinbefore mentioned are appropriately identified by the printed notations.

Having fixed the screen separation as above, a maximum diaphragm opening is calculated (see 20 Fig. 2) so that the secondary beams of light, indicated at 8 and 9, forming a penumbra around the central dot as obtained in half tone making with a cross line screen, just cover all intervening spaces on the screen supporting medium 6. Thus 25 according to this invention, the minimum diaphragm opening is the controlling factor in the disposal of the cross line screen. With these limits of diaphragm openings, the exposure may be made with a continuously opening or closing 30 diaphragm, and the rate of opening or closing of the diaphragm will determine the rate of slope of the density wedge. In actual practice it is unnecessary to make a continuous exposure with such a constantly varying diaphragm. I have discovered for instance that if, say, six exposures are 35 made with the two extreme diaphragm openings as mentioned above and four intervening ones, a screen is obtained with practical working quality. That is to say, I have discovered that with a $2\frac{1}{4}$ 40 diameter, 18 inch focus process lens and a camera extension of $29\frac{1}{4}$ inches, with a 60 lines per inch cross line screen of the 1:1 variety separated from the contact screen supporting medium by $1\frac{1}{4}$ inches, with the light reflected from a pair 45 of arc lights playing upon a sheet of blotting paper at the proper copy distance, and the commercial process film as the contact screen material, (said film held under "vacuum" contact against glass in the plate holder and in substantial parallelism to the light intercepting screen), a 14 50 second exposure successively through each of the following diaphragm openings

55	.075 inch diameter
	.107 inch diameter
	.151 inch diameter
	.215 inch diameter
	.303 inch diameter
	.430 inch diameter

60 will produce an image which, upon development, yields the half-tone contact screen. This photographic development should be of a character to bring out the exposure, and it has been found satisfactory to use a developer registering tone. 65 For my purpose I found it convenient to use the ordinary so called commercial D-11 developer diluted with two volumes of water, developing for say five minutes at 65 to 70° F.

70 It is pointed out that the intercepting cross line screen 5 is not in half-tone relation according to the ordinary conception of the term, for it is generally conceded that half-tone relation with the screen used is approximately ninety times the diameter of the screen opening, which 75 would result in a separation ranging from $\frac{1}{8}$ to

$\frac{3}{4}$ of an inch, while I use $1\frac{1}{4}$ inches separation. In using a cross line screen with separation in half-tone making, it is customary to assume for an 18 inch focus lens that the camera extension is to the screen separation as the diaphragm 5 opening is to the screen opening. For the purpose of preparing my half-tone contact screen, however, I have found that this ratio does not give the best results, but rather the camera extension distance minus the focal length of the 10 lens is to the screen separation as the minimum diaphragm opening is to the screen opening. In other words, for the purposes of my calculation, I find that instead of using the camera extension distance alone, as is the custom in present 15 half-tone calculation, I must use the dimension expressed by the difference between the camera extension and the focal length of the lens, wherefore it may be seen that the screen separation used in preparing my half-tone contact screen, 20 as calculated from the minimum diaphragm opening used, is intermediate between that required by calculation as used today and a screen separation as would be used in ordinary practice.

It is believed that novelty in the preparation 25 of my contact half-tone screen resides in the selection of proper screen separation for the minimum diaphragm used. It is pointed out with particular reference to Fig. 3 that the maximum density in the area covered by the light passing 30 through the openings of the intercepting cross line screen, is at the central point as indicated by the numeral 11 and that there is a decrease in the density in all directions from this central point. Conversely, the points farthest removed 35 from the above mentioned central dense spot and indicated at 12, are the lightest or least dense portions and these lightest points underlying the intersections of the lines on the cross line screen. Therefore, considering the space on the half-tone contact screen medium lying between the 40 lines A—A, B—B, C—C, D—D and underlying four adjacent openings of the intercepting cross line screen, it is seen that four maximum density 45 points appear at the centers of the four areas underlying said adjacent openings of the intercepting screen. Equidistant between these four maximum density points there appears the point of minimum density, with the shading between this minimum point and the maximum points 50 whose slope depends upon the emulsion used for the half-tone contact screen, and the rate of opening of the diaphragm when the diaphragm is opened continuously, or the number of separate exposures made at different diaphragm openings, 55 as well as the time of the individual exposures.

Fig. 3 is a representation magnified to substantially sixty times the dimension of the actual screen produced in order to better illustrate the variable density from point maximum to point minimum.

Thus it will be seen that by this invention there is produced a contact half-tone screen which when highly magnified will show a plurality of geometric areas each of which has a 65 variation of tone. That is to say, it will be seen that the center of each area appears as a point which is sharply focused, and that the remaining points making up the balance of the area appear radiating from the center point in progressive 70 degrees of focus as well as progressive change of density or tone.

It is pointed out that what I have accomplished is the preparation of a printing mask which will 75 pass an amount of light through, in area and

quantity, equivalent to that passed by an intercepting cross line screen when a separation is maintained between the cross line screen and the sensitized medium. It is further pointed out 5 that for a universal rendition of copy from the most contrasty to the softest, a mask of the above nature is necessary. Consider for a moment the reproduction of the most extreme contrast, the minimum density, at the minimum point on the 10 screen, is required to mask out reflected light from the extreme black portions of the copy. On the other hand, the densest portion, being a point, allows the printing with the maximum light to the finest point. On the black copy at the maximum 15 point the printing can be carried to the desired point, even to the extent of lightening the whites of the copy, while the blacks will register their proper values through the points of minimum density and areas surrounding them. For 20 use in the camera, in contact with the sensitive medium, this screen enables a universal rendition of all types of copy.

Where an adjustment of contrast is desired, as is customary in the making of half-tones with 25 the intercepting screen, adjustment of contrast is obtained by what is known as flash on white copy, followed by the regular exposure on the copy to be reproduced. It may be seen that this shifts the shadow rendition toward the high light without 30 markedly affecting the extreme high light. This same flash is desirable with the contact half-tone screen in some cases. In fact the making of half tones with the contact half tone screen, thereby eliminating the element of screen separation, 35 enables the making of half-tones by the unskilled photographer, since there must be dealt with only the question of flash and total exposure. The relation of diaphragm openings to screen separation, and camera extension or change of size of 40 copy, is entirely dispensed with.

Therefore, it will be understood that this invention is not limited to the specific examples given in the preceding paragraphs in order to make the disclosure more clear, since the smaller

diaphragm openings may vary in size, though they will be relatively minute, there may be a wide range of openings to the largest. From the example previously cited, the smallest diaphragm gives a calculated "f." number of 240 according 5 to the ratio of focal length of lens (18) to the diameter of the smallest diaphragm (0.075), whereas by the same formula ratio the largest diaphragm (0.430) will give the value of f. 42.

Furthermore, the calculation of the largest dia- 10 phragm to be used is not always as exact as that of the smallest or screen-separation-determining diaphragm. In other words, with a largest dia- phragm opening calculated for exact coverage, there may have to be made a slight adjustment 15 to insure coverage. This adjustment will depend upon the sensitive emulsion used, and with the developer in which the contact screen emulsion is developed. The adjustment is less the more sensitive the recording medium is to the register 20 of tones from light exposures.

It is obvious that those skilled in the art may vary the details of construction as well as arrangements of parts without departing from the spirit of the invention, and therefore it is not de- 25 sired to be limited to the foregoing except as may be required by the claim.

What is claimed is:—

In the production of a contact screen for uni- 30 versal application in photographically making half-tones, and wherein there is employed a screen in a camera for intercepting the light rays reaching the photographically sensitized surface of the contact screen medium, the method of de- 35 termining the separation distance of the light intercepting screen from the contact screen me- dium according to the formula $A:x=B:C$ in which x is the separation distance, A is the dif- ference between the camera extension and the focal length of the camera lens, B is the diameter 40 of the smallest lens diaphragm opening used, and C is the dimension of one of the openings of the light intercepting screen.

CHARLES W. BENNETT.
